By Clarence O'Brien, Attorney

UNITED STATES PATENT OFFICE

JOHN V. LONGAN, OF ARCHER CITY, TEXAS

SHOPPING WAGON

Application filed June 17, 1930. Serial No. 461,748.

The present invention relates to a shopping wagon or like construction wherein a box or the like is mounted on a mobile supporting structure and the object of the invention is to provide a device of this nature which is exceedingly simple in its construction, inexpensive to manufacture, easy to handle, strong and durable, compact and convenient in its arrangements of parts, and thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the device embodying the features of my invention,

Figure 2 is a top plan view thereof,

Figure 3 is a horizontal section therethrough taken substantially on the line 3-3 of Figure 1,

Figure 4 is a vertical section taken substantially on the line 4-4 of Figure 2,

Figure 5 is a detail section taken substantially on the line 5-5 of Figure 1, and

Figure 6 is a perspective view of one of the legs.

Referring to the drawing in detail it will be seen that the numerals 5 denote four tubular legs which merge at their upper ends into corner pieces comprising a pair of plates 6 right angularly disposed in respect to each other. The numeral 7 denotes a rectangular box, the corners of which are receivable between the plates 6 and engaged therewith by means of screws 8 or other suitable fastening elements.

One corner of the box 5 is provided with an extension 9 rising therefrom with an adjustable strap 10 across the ends thereof. A shelf 11 is provided at its corners with notches to receive lower portions of the legs 5 and to be fastened thereto by means of screws 12 or like fastening elements.

Casters 14 are mounted in the lower ends of the legs.

The present invention has been devised for general purposes in connection with custom-

ers shopping in retail stores, or for use in the homes of individuals in simplifying the work of the housewives in performing the necessary household duties. The device as described above is a combination shopping wagon and baby cart. It may be used by customers in a retail grocery store where said customers go from one part of said store to another making purchases and carrying said purchases with them. One corner of said device has an extension 9 so that a baby may be placed and held in position by the strap 10 thereby making it possible for the mother to select her groceries and other merchandise and to carry the child with her.

The invention is further designed to serve as a combination tea wagon and baby cart. The box of said device in which the baby rides will furnish it a safe and comfortable place for such purposes and at the same time there will be plenty of room in the box or on the shelf of said device to serve as a tea wagon or to hold the groceries or other merchandise when used for shopping. The invention is further designed for use in a grocery store or like establishment by the merchant in distributing his grocery or merchandise from one part of the store to another and placing the same on the shelves in the desired location.

The invention is also further designed to enable said merchant to carry the merchandise or groceries and distribute the same without the necessity of stooping while loading or unloading supplies, and without the necessity of carrying said merchandise from one part of the store to another, or the merchant might use this conveyance as part of the equipment of the store for use by the patrons in such store.

It is intended that this invention might be used in drug stores, stationary stores or other retail businesses or even in wholesale houses.

It is thought that the construction, utility and advantages of this invention will now be quite apparent to those skilled in this art without a more detailed description thereof.

It is apparent that the present embodiment of the invention has been described in considerable detail merely for the purposes of

exemplification since in actual practice it attains the features of advantage enumerated as desirable in the statement of the invention and the above description.

5 It will be apparent that changes in the details of construction, and in the combination and arrangement of parts may be resorted to without departing from the spirit or scope of the invention as hereinafter claimed or 10 sacrificing any of its advantages.

Having thus described my invention, what I claim as new is:

1. In a device of the class described, a plurality of legs merging into corner pieces, a 15 box having its corners in the corner pieces, means holding the box in the corner pieces, and casters on the bottoms of the legs, a shelf across the lower portions of the legs, and means holding the shelf to the legs, said 20 box having a corner extension rising therefrom, and a strap across the ends of said extension.

2. A device of the class described comprising a rectangular shaped box having an upwardly extending part at one corner thereof, said part being of right angular shape with each portion thereof forming an extension of a side of the box, a strap having its ends connected with the two edges of the extension 30 whereby an infant can be placed in said corner of the box with the extension forming a rest for the infant's back and the strap acting to hold the infant in position, legs connected with the box, and castors in the 35 lower ends of the legs.

In testimony whereof I affix my signature.
JOHN V. LONGAN.
